FIG. 2.

INVENTOR

ELMER J. TOWLE

BY Henry Gifford Hardy,

ATTORNEY

UNITED STATES PATENT OFFICE

166,107

ROSARY BRACELET

Elmer J. Towle, San Francisco, Calif.

Application March 2, 1951, Serial No. 14,356

Term of patent 14 years

(Cl. D45—4)

To all whom it may concern:

Be it known that I, Elmer J. Towle, a citizen of the United States of America, residing in the city and county of San Francisco, State of California, have invented a new, original, and ornamental Design for a Rosary Bracelet, of which the following is a specification, reference being had to the accompanying drawing forming part hereof, wherein:

Figure 1 is a rear perspective view of a rosary bracelet embodying the new design, and

Figure 2 is a front perspective view of the bracelet; and

Figure 3 is a developed plan view thereof.

I claim:

The ornamental design for a rosary bracelet, as shown.

ELMER J. TOWLE.
